UNITED STATES PATENT OFFICE.

CHARLES W. LE COUNT, OF NORWALK, CONNECTICUT.

IMPROVEMENT IN ADJUSTABLE MANDRELS.

Specification forming part of Letters Patent No. 55,681, dated June 19, 1866.

To all whom it may concern:

Be it known that I, CHARLES W. LE COUNT, of the town of Norwalk, county of Fairfield, and State of Connecticut, have invented new and useful Improvements in the Mode of Constructing Adjustable Mandrels for the use of Lathes; and I do hereby declare that the following is a correct description thereof, reference being had to the accompanying drawings, and to the letters of reference marked thereon.

The nature of my invention consists in the arrangement of a mandrel for lathes with adjustable sliding keys.

To enable others skilled in the art to make and use my invention, I will proceed to describe the construction and operation.

In the drawings, Figure 1 is a side view of the mandrel before the socket, thimble, and keys are placed in position; Fig. 2, a sectional view of same when the socket, thimble, and keys are in operation; Fig. 3, side view of one of the keys.

The mandrel A, Fig. 1, I form with a drilled hole at each end for the lathe-centers in the usual manner.

In the parallel part at A, I cut a screw with a fine thread to receive the socket B, which has an internal or female thread to correspond with the thread on the mandrel A. On the forward end of the socket B, I cut an external thread of about double the pitch of the thread on the mandrel A. I then make a thimble, C, with an internal thread to screw onto the external thread of the socket B. This thimble C has a square projection, G, at the forward end, internally, to catch on and press on a similar projection, H, of each of the sliding keys F to bring them back and cause them to slide in the inclined grooves E of the mandrel to enlarge their diameters at the level part where the article (marked D) or any other is put on to be operated on.

The forward part of the mandrel, Fig. 1, say about half-way, is prepared to form the adjusting part of the same by being made tapering in the usual mechanical manner. In this taper part I form three or four grooves, E, on the periphery of the same of a suitable size and depth, and the sides a little dovetailing, to receive the adjusting keys F, which are made to fit in the grooves E and slide in the same.

At the back end of the keys F (see Fig. 3) I make a square projection, G, to correspond and act with the projection in the interior of the thimble C. These projections are the means that tighten the keys F to the object to be operated on by drawing them back and up the inclined groove in the tapered part of the mandrel by the combined movement of the socket B and thimble C.

The keys F are made parallel and are sunk down in strips, as shown in Fig. 3, to give that part a perfectly level horizontal space or bearing when placed in the grooves; and it is the sliding up the grooves that expands their diameter to fasten firmly the article to be turned.

To operate my mandrel, first screw on the socket B; then place the keys F in the grooves E; then place on the thimble C, the keys being sufficiently forward and loose; now put on the article, (see the piece marked D;) then screw the thimble C onto the socket B, screw back both socket and thimble, and the projection in the thimble will draw back the keys F up the inclined grooves E, and the parallel level parts of the keys will expand in diameter to firmly fasten the article D for operation.

When required to take off the finished article, screw forward the combined socket B and thimble C, and the forward end of the socket B will press against the end projection, H, of the keys F and force them down the inclined grooves and loosen the whole, so that the article can be taken off.

Flat spaces are made on the mandrel for the use of a wrench and a pin or other device for the dog of the lathe face-plate to carry round the same in the usual manner.

There are no limits to the size of this adjustable mandrel, and it is both useful and convenient.

What I claim as my invention, and desire to secure by Letters Patent, is—

The arrangement of the sliding keys F, socket B, and thimble C, in combination with the mandrel A, in the manner and for the purpose substantially as herein described.

C. W. LE COUNT.
